FLOWER POT SUPPORT OR THE LIKE

Ralph Cucullo, 118 Mount Joy Place,
New Rochelle, N.Y.

Filed Jan. 28, 1964, Ser. No. 78,393

Term of patent 14 years

(Cl. D35—3)

FIG. 1.

FIG. 4.

FIG. 2.

FIG. 5.

FIG. 6.

FIG. 3.

FIGURE 1 is a perspective view of a flower pot support or the like, showing my new design;

FIG. 2 is a front elevation thereof;

FIG. 3 is a top plan view thereof;

FIG. 4 is a bottom plan view thereof;
FIG. 5 is a top plan view thereof in a collapsed position; and

FIG. 6 is a front elevation thereof as shown in FIG. 5.

I claim:

The ornamental design for a flower pot support or the like, as shown.
